Primary Examiner — Sheryl Lane*Assistant Examiner* — Mark T. Philipp(74) *Attorney, Agent, or Firm* — Phillips Winchester(57) **CLAIM**

The ornamental design for a drill bit, as shown and described.

DESCRIPTION

FIG. 1 is a front perspective view of a drill bit including a cutting tool according to a new design, with the back perspective view being identical; and, FIG. 2 is a top plan view thereof.

The broken lines in the drawings depict portions of the drill bit that form no part of the claimed design.
